PERCIVAL ERNEST PETHERICK, OF GIBSON, NEW ZEALAND, ASSIGNOR TO THE PETHERICK PATENT ADVERTISING SYSTEM LIMITED, OF AUCKLAND, NEW ZEALAND.

LANTERN-SLIDE-DISPLAYING APPARATUS.

1,354,682.

Specification of Letters Patent.

Patented Oct. 5, 1920.

Application filed October 11, 1919. Serial No. 330,046.

To all whom it may concern:

Be it known that I, PERCIVAL ERNEST PETHERICK, subject of the King of Great Britain, residing at Stout street, Gisborne,

5 in the Dominion of New Zealand, have invented a new and useful Improvement in Lantern-Slide-Displaying Apparatus; and I do hereby declare the following to be a full, clear, and exact description of the same.

10 This invention relates to apparatus for use in displaying lantern slides of the class in which the slides are adapted to be automatically displayed in regular rotation by the mechanism employed.

15 The invention is designed specially to provide a new and improved form of slide carrier or magazine in which the slides are vertically disposed one alongside the other and which in its operation is caused to move 20 the slides one by one beneath a slide holder arranged in the projector apparatus, combined with improved means whereby as each slide comes beneath such holder, it is raised into the holder and simultaneously displaces 25 the slide already in the holder so that such slide will fall back into its proper division of the carrier.

The invention is illustrated in the accompanying drawings, in which:—

30 Figure 1 is a side elevation of the complete apparatus.

Fig. 2 is a plan thereof with certain parts shown broken away to clearly illustrate the parts beneath.

35 Fig. 3 is a sectional elevation of the slide carrier or magazine.

Fig. 4 is a plan, on an enlarged scale, of the slide carrier and slide holder.

Fig. 5 is a side elevation thereof.

40 Fig. 6 is a front elevation of the slide holder showing in cross section, the slide carrier or magazine passing beneath it.

Fig. 7 is a sectional elevation through the slide holder and slide carrier or magazine.

45 The carrier, or "magazine" as it will be hereinafter termed, is therefore formed as a circular box A having outer and inner vertical walls A'—A² arranged concentrically with one another at an approved distance

50 apart. Each wall is formed with vertical grooves B in it arranged in radially coincident lines with those of the other so that the slides C to be displayed may be held upright in the box one alongside the other by

55 fitting at their side edges into the respective

radially opposite grooves, as shown clearly in Fig. 4. The slides themselves therefore are held in lines radial to the center of the magazine.

The magazine thus constructed is mounted 60 on a table or support D so that it may rotate on an axis coincident with its center and cause the slides to pass beneath the slide holder E that is built upon such table and arranged in a line with approved projector 65 apparatus U also fixed to such table.

For convenience in the construction and mounting of the apparatus and the operating means, the central portion of the magazine bottom is preferably removed, so that 70 in actual fact, the magazine is formed as an annular shaped box. It is mounted on an annular slide plate F fixed to the table D and having guides f to keep it from moving laterally while allowing it to rotate in the 75 necessary manner. The bottom of the magazine box is pierced with slots G that extend in a line radially coincident with the lines assumed by the slides when in the box, one of such slots being positioned beneath each 80 slide. A single slot G' is formed in the slide plate F and the table D, in a line vertically beneath the slide holder E, such slot being so disposed that the slots G coincide therewith, one by one as the magazine is 85 given intermittent rotatory motion.

The slide holder is formed by two vertically extending cheeks E' and E² fixed to the table D and disposed opposite one another on opposite sides of the annular magazine box A so that the said box thus travels between them, as clearly shown in Figs. 4 and 6. Each of these cheeks is formed with a vertically extending groove e in its relatively inner face, such grooves being arranged so that they overlap the respective edges of the box A and are respectively coincident with the lines of grooves in the inner and outer walls of such box. Thus a slide C positioned in the box beneath such 90 grooves e may be raised from the box into display position in the grooves by pushing it up from beneath to the necessary height.

In the working of the apparatus, a slide is designed to be raised into display position 105 in the holder E, the magazine then to be rotated through the proportion of a rotation requisite to bring the next slide into position beneath the holder, and then after the necessary interval of time, to raise such 110

second slide into the holder, and at the same time move the first slide out of the holder and cause it to drop back into the grooves in the magazine from which it was raised, which grooves have moved on a step.

Means for effecting these objects are shown in the drawings, the raising and feeding means being shown particularly in Figs. 1 and 2 and the slide displacing means in 10 Figs. 4 to 7.

Beneath the table D, an operating wheel H is mounted to rotate horizontally and is continuously driven by any suitable means at any desired rate. A lever J is pivoted 15 to a standard J' fixed beneath the table and one end of this lever is pivoted to a lifting bar K that extends vertically upward in a suitable guide K' and passes into the slot G'. When this bar is down 20 its top is positioned just below the level of the magazine, as shown in Fig. 6, so that the magazine may rotate freely. The bar is made of such a shape in cross section that it may pass up into the slot G in the magazine bottom, at the time being above it, and engage the bottom of the corresponding slide so as to lift such slide from the magazine, up into the slide holder, when it is raised the required amount by the operation 25 of the lever J. The other end of the lever is furnished with a roller M extending laterally from it and projecting across beneath the edge of the wheel H. A cam H' of suitable shape is fixed to the wheel's 30 bottom surface in a position to engage the roller M so that on each rotation of the wheel, the lever will be operated to raise the bar K the requisite amount, and then release it so that it may drop back by its 35 own weight.

The outer periphery of the magazine is formed with ratchet teeth A³ thereon, spaced apart distances corresponding to the distances apart of the slides in the magazine. Mounted to slide on the table D in a line tangential to the ratchet wheel edge, 45 is a block N that carries a spring pawl tooth N' positioned to engage the ratchet teeth and move the magazine as the block is moved to and fro. The block is mounted in a guide slot n in the table and has a portion projecting beneath the table, where it is attached to one end of a horizontal connecting bar O the other end of which is pivotally attached to a lever O' pivoted at one end to a fixture O² beneath the table and at its other end overlying the top of the operating wheel H. A roller h projects upward from such wheel and the end of 50 the lever O' is so positioned that as the wheel rotates this roller will engage the end of the lever, move it across for a distance and then pass on. The amount of movement of said lever is adjusted to cause 55 the block N to be moved the necessary dis-

tance out to turn the magazine through the precise angular distance necessary to position the next slide beneath the slide holder, and this may be effected by mounting the pin which carries the roller h in a slot h' 70 formed radially in the wheel and providing for it being locked at any point in such slot. A strong spring P is fixed to the back end of the block N and to the table, to return the block and also the lever O' to 75 their normal positions after the roller h has released the lever, the pawl N' sliding back over the ratchet and engaging behind the next tooth, ready for the next feeding action. 80

Thus each rotation of the wheel H will cause a slide to be raised and the next slide to be brought into the position to be raised, and these operations will occur at the proper intervals apart and as adjusted by the relative 85 positions of the cam H' and the roller h upon the wheel.

Each slide, as it is raised into the slide holder, engages at its two side edges respectively beneath the pawls R—R' fixed 90 upon a spindle R² mounted to extend across between the cheeks E' and E² of the slide holder and tips such pawls up until the slide has passed by their free ends, this position being indicated in dotted lines in 95 Fig. 7, and then allows the pawls to fall back onto shoulders e' formed in the sides of the grooves e. The slide then also drops down until its bottom rests upon these pawls and it is thus held in the display position. The back of the slide, near its two edges, is engaged by pressure springs S—S' fixed upon a spindle S², said springs normally bearing inward and pressing the slide forward to the front edges of the 100 grooves. These springs are adapted to be turned back as the slide is being raised by connecting the two spindles R² and S² by the cranks T and connecting rod T' so that the turning of the pawls upward will cause 110 the spindle S² to be rotated and the springs S and S' to be turned back. When the pawls fall, the springs will be turned forward again, the falling of the pawls being insured by means of the helical spring t attached to the crank upon the spindle R² and to the cheek E'. 115

When the next slide is raised and engages the pawls, the slide already in position will be tipped back over the rear of the pawls, 120 the grooves e being made wide enough to permit of such movement, and will slide down into the grooves B of the magazine from which it was lifted. These grooves will have been fed rearward one step, and will therefore be out of parallel with the slide to be dropped into them. The pawls are therefore so designed that the one at the inner end of the spindle will throw the inner edge of the slide back just a sufficient 125 amount to clear the rear of the pawls. 130

distance to position such edge above the groove in the inner wall of the magazine as shown in Fig. 7, while that at the outer end of the spindle is made with a tail ex- 5 tension r (shown by dotted lines in Fig. 5) so that it will throw the outer edge of the slide across into position to pass into the groove in the outer wall of the magazine. Consequently the slide will be accurately 10 positioned to drop back into its proper grooves.

These operations are repeated continuously, the slides being raised to display position, one after the other, in the desired 15 order. The machine may be stopped at any time and restarted at will by controlling the mechanism driving the wheel H.

During the changing of the slides in the slide holder, the projecting light may be 20 automatically shuttered so that no confused pictures will be thrown onto the screen. This may be effected by the movement of the slide lifting lever J, which as it rises, allows shutters U' (Fig. 1) to close 25 under the action of a spring, and as it falls, opens such shutters, the said lever being connected to the shutters by the cord U².

I claim:

1. In a projection apparatus, the combination of a slide holder; a slide magazine located beneath the holder and rotatable step by step with relation thereto; mechanism for raising the slides one at a time from the magazine into the holder; and mechanism 35 for rotating the magazine one step to present a new slide to the holder while a slide is being displayed therein.

2. In a projection apparatus, the combination of a slide holder; a slide magazine located beneath the holder and rotatable step by step with relation thereto; mechanism for raising the slides one at a time from the magazine into the holder; mechanism for rotating the magazine one step to present a new slide to the holder while a slide is being displayed therein; and means operated 45 by the entrance of the new slide into the holder to return the previously-displayed slide to the magazine.

50 3. In a projection apparatus, the combination of a slide holder; a slide magazine located beneath the holder and rotatable step by step with relation thereto; mechanism for raising the slides one at a time from the magazine into the holder; mechanism for rotating the magazine one step to present a new slide to the holder while a slide is being displayed therein; and means engaged 55 by the new slide as it enters the holder for 60 returning the previously-displayed slide to the magazine.

4. In a projection apparatus, the combination of a slide holder; a slide magazine located beneath the holder and rotatable step 65 by step with relation thereto; mechanism for

raising the slides one at a time from the magazine into the holder; mechanism for rotating the magazine one step to present a new slide to the holder while a slide is being displayed therein; and pivotally-mounted 70 supporting means carried by the holder for retaining a slide in display position therein, said supporting means being operatively engaged by an in-coming slide to return the previously-displayed slide to the 75 magazine.

5. In a projection apparatus, the combination of a slide holder; a slide magazine located beneath the holder and rotatable step by step with relation thereto; mechanism for raising the slides one at a time from the magazine into the holder; mechanism for rotating the magazine one step to present a new slide to the holder while a slide is being displayed therein; and means operated automatically 80 during the entrance of the new slide into the holder for ejecting the previously-displayed slide and returning it to the magazine.

6. In a projection apparatus, the combination of a slide holder; a slide magazine for presenting the slides one at a time to the holder; operating mechanism for the magazine; mechanism for transferring the slides from the magazine to the holder; an operating 90 wheel; an operating rod for one of said mechanisms mounted for vertical rocking movement; an operating rod for the other mechanism mounted for horizontal rocking movement, said rods terminating at 95 their free ends adjacent opposite sides of said wheel; and devices on opposite sides of said wheel for actuating said rods.

7. In a projection apparatus, the combination of a slide holder adapted to support 105 the slides one at a time in stationary display position therein; a slide magazine; means for transferring the slides from the magazine to the holder; and means for moving the magazine with relation to the holder 110 while a slide is in its stationary display position in said holder to bring a new slide to transferring position.

8. In a projection apparatus, the combination of a slide holder; a rotatable, circular 115 slide magazine provided with a peripheral series of teeth; mechanism for transferring the slides one at a time from the magazine to the holder; and mechanism co-operative with said teeth for imparting a step-by-step 120 rotary movement to the magazine to bring the slides successively into position to be acted on by the transfer mechanism, said rotating mechanism being timed to operate while a slide is in display position in the 125 holder.

9. In a projection apparatus, the combination of a slide holder; a circular slide magazine rotatable about a central axis and provided with radially-disposed slide con- 130

ainers; mechanism for imparting a step-by-step rotary movement to the magazine to present the slides one at a time to the holder; and mechanism for simultaneously introducing a new slide into the holder and returning the one already therein to its particular container in the magazine.

10. In a projection apparatus, the combination of a slide holder; a circular slide magazine rotatable about a central axis and provided with radially-disposed slide containers; mechanism for imparting a step-by-step rotary movement to the magazine to present the slides one at a time to the holder, 15 said mechanism being timed to act while a slide is in display position in the magazine; and mechanism for simultaneously introducing a new slide into the holder and returning the one already therein to its particular container in the magazine.

11. In lantern slide display apparatus, the combination with a slide magazine of circular form constructed to hold the slides one behind the other in radial lines and with 25 means for imparting intermittent partial rotation to such magazine in a horizontal plane and upon a central axis and means for raising the slides one by one vertically upward from the magazine in alternation 30 with the partial rotary movements of the magazine, of a slide holder fixed above the magazine and positioned so that the slides therein pass beneath it in the rotation of the magazine, such slide holder being formed

with grooves to receive the side edges of a 35 slide and having a pair of pawls arranged at the respective ends of a transversely mounted spindle, such pawls being positioned and constructed to be engaged by the upwardly moving slide as it enters the 40 holder and raised to allow the slide to pass and then to fall to provide rests upon which the bottom edge of the slide will rest and being also formed with cam faces on their backs to direct the slide down across the 45 back and into the magazine on their next upward turning movement, substantially as specified.

12. In lantern slide display apparatus, the combination with a slide holder constructed 50 as described in claim 11, of a second spindle mounted parallel to the pawl spindle and connected with it so as to be turned thereby, such second spindle having pressure springs secured thereon adapted to be turned 55 into engagement with the slide in the holder when the pawls are down and to be turned out of engagement as the pawls are lifted, and a spring controlling such connections and normally keeping the pawls down, substantially as and for the purposes specified.

In testimony whereof I have signed this specification in the presence of two subscribing witnesses.

PERCIVAL ERNEST PETHERICK.
